SECTIONAL BOX WRENCH

Malcolm P. Rasco, Port Arthur, Tex.

Application February 2, 1951, Serial No. 209,120

5 Claims. (Cl. 81—121)

1

This invention relates to a wrench, and more particularly to a box type sectional wrench.

An object of the invention is to provide a box type wrench wherein the head embodies two sections movable relative with respect to each other.

Another object of the invention is to provide a box type wrench wherein the head embodies two sections, one of said sections being fixed and the other section being movable toward and away from the fixed section.

Another object of the invention is to provide a box type wrench wherein there is provided a positive locking means for locking the two sections of the head together when the sections have been moved to closed position.

The above and still further objects and advantages of the present invention will become apparent upon consideration of the following detailed description taken in conjunction with the accompanying drawings, wherein:

Figure 1 is a top plan view of a sectional box type wrench constructed according to the present invention, with parts broken away and shown in section;

Figure 2 is a side elevational view of the sectional box type wrench of the present invention, shown in a position for placement on a screw fitting of a flexible tubing;

Figure 3 is an enlarged fragmentary sectional view taken along the line 3—3 of Figure 1; and

Figure 4 is an enlarged fragmentary sectional view taken along the line 4—4 of Figure 1.

Referring now more particularly to the drawings, wherein like reference numerals have been used throughout the several views to designate like parts, there is shown the sectional box type wrench of the present invention, generally designated by the reference numeral 10, which includes an elongated shank 11 and sectional box type heads 12 and 13 carried contiguous to each end of the shank. Since each of the heads 12 and 13 is of a like structure, it will suffice to describe only one in detail.

The head 12 embodies a mounting plate 15 which projects from the adjacent end of the shank 11 and is formed integrally with the shank, or secured thereto. Formed on the mounting head or secured thereto is an arcuate, fixed jaw 16 which projects from the mounting plate 15. Arranged in a closed position in face-to-face relation with respect to the fixed jaw 16 is a movable jaw 17 which is mounted on the fixed jaw for swinging movement from the closed position to an open position spaced from the fixed jaw and illustrated in phantom in Figure 1.

2

1. The jaws 16 and 17, which are of the same arcuate length, are pivotally connected together by means of spaced ears 18 and 19 formed contiguous to one end of the movable jaw 17, an ear 20 formed integrally with or secured to the adjacent end of the fixed jaw 16, and a pivot pin 21 straddling the ears 18 to 20, inclusive.

As clearly shown in Figures 1 and 4, the end faces of the jaws 16 and 17 remote from the pivot pin 21 abut and confront each other in the closed position of the fixed and movable jaws. The end face of the movable jaw 17 is provided with a projecting lug 22 which is receivable within a complementary recess 23 provided in the adjacent end face of the jaw 16 when the jaws are in the closed position of Figure 1.

Projecting outwardly from the movable jaw 17 is a shoulder 24 which is receivable within a complementary seat 25 provided in the mounting plate 15 upon movement of the movable jaw 17 into the close position. The shoulder 24 is provided with a slot 26 and the mounting plate 15 is provided with a slot 27, the slots 27 and 26 cooperating with each other in the closed position of the jaws to define an elongated, closed-ended channelway 28. Arranged within the channelway 28 is a latch 29 which has one end received within the slot 26 of the shoulder 24, and has the other end receivable within the slot 27 of the mounting plate 15. Extending transversely of the end of the latch 29 received within the slot is a pivot pin 30 which engages adjacent portions of the shoulder 24 and mounts the latch for pivotal movement from a non-locking position exteriorly of the slot 27 of the mounting plate 15 to a locking position therein. As clearly shown in Figure 3, the latch piece 29 is provided with an upwardly projecting finger piece 31 and a downwardly projecting finger piece 32 which can be manually engaged to effect pivotal movement of the latch from the locking position within the channelway to a non-locking position wherein the movable jaw 17 is free to swing to the open position illustrated in phantom in Figure 1.

As clearly illustrated in Figure 3, the end of the latch 29 contiguous to a terminating end wall 33 of the slot 26 is provided with an inwardly extending socket 34 which mounts a ball 35, the ball 35 being biased by a spring 36 into engagement with a detent depression 38 provided in the end terminating wall 33 of the slot 26. The spring biased ball 35 accordingly facilitates releasable securing of the latch 29 in the locking position in the slots 26 and 27.

As clearly illustrated in Figure 1, the fixed and movable jaws 16 and 17 cooperate to define a closed socket 37. The socket may be of any design, so that any socket formation can be employed in accordance with the use to which the wrench is going to be put. Also, the socket of the head 13 can likewise be formed in accordance with the needs of the user. It is to be noted that the fitting engaging faces of the socket 37, generally designated by the reference numeral 38, are triangularly notched to form gripping teeth for gripping the fitting to be loosened or tightened.

In actual use, the latch 29 is moved out of the locking position illustrated in Figure 3, permitting the movable jaw 17 to swing to the broken line position illustrated in Figure 1. As clearly shown in Figures 1 and 2, the wrench head 12 can then be engaged about a flexible tubing 40, and the movable jaw swung to the closed position of Figure 1, whereupon the latch 29 can be once again moved into the locked position. The wrench is then moved longitudinally of the tubing 40 and engaged about the fitting 41, whereupon the fitting can be turned to loosen or tighten the fitting.

Although only one embodiment of the wrench of the present invention has been described, it is readily apparent that numerous modifications can be made without departing from the spirit of the invention as set forth in the appended claims.

What I claim is:

1. In a socket wrench, a plate, a fixed semi-circular jaw projecting from said plate at one side of said plate, said fixed jaw having an inner end located adjacent to said plate and an outer free end, an abutment on the inner end of the fixed jaw, a complementary semi-circular movable jaw, means pivoting one end of said movable jaw to said free end of the fixed jaw, the other end of the movable jaw being formed with an abutment arranged to engage the abutment of the fixed jaw in the closed position of the movable jaw, a projection on said movable jaw adjacent to said other end thereof, said projection projecting radially outward from the movable jaw, the side of said plate remote from said one side thereof being formed with a notch conformably shaped to receive said projection in the closed position of the movable jaw, an edge of said notch being provided with a slot opening therethrough and said projection having an edge provided with a slot arranged to register with the plate slot in the closed position of the movable jaw, a latch pivoted in the projection slot and having an outer end portion arranged to be normally positioned in the plate slot so as to hold the movable jaw in closed position, said latch being pivotable to a position in which its outer end portion is removed from the plate slot and the movable jaw is free to be pivoted to open position.

2. In a socket wrench, a plate, a fixed semi-circular jaw projecting from said plate at one side of said plate, said fixed jaw having an inner end located adjacent to said plate and an outer free end, an abutment on the inner end of the fixed jaw, a complementary semi-circular movable jaw, means pivoting one end of said movable jaw to said free end of the fixed jaw, the other end of the movable jaw being formed with an abutment arranged to engage the abutment of the fixed jaw in the closed position of the movable jaw, a projection on said movable jaw adjacent

to said other end thereof, said projection projecting radially outward from the movable jaw, the side of said plate remote from said one side thereof being formed with a notch conformably shaped to receive said projection in the closed position of the movable jaw, an edge of said notch being provided with a slot opening therethrough and said projection having an edge provided with a slot arranged to register with the plate slot in the closed position of the movable jaw, a latch pivoted in the projection slot and having an outer end portion arranged to be normally positioned in the plate slot so as to hold the movable jaw in closed position, said latch being pivotable to a position in which its outer end portion is removed from the plate slot and the movable jaw is free to be pivoted to open position, and spring pressed detent means acting between the projection slot and the latch for holding the latch releasably in its normal locking position.

3. In a wrench, a pair of complementary semi-circular jaws, one of said jaws being stationary and the other relatively movable, a plate fixed on and extending radially outward from the radially outward side of said stationary jaw at one end of said stationary jaw, said stationary jaw having a free end, said movable jaw having an end pivoted to the free end of the stationary jaw and having another end, said one end of the stationary jaw and said other end of the movable jaw terminating in abutments arranged to engage in the closed position of the movable jaw, one of said abutments being provided with a recess and the abutment of the other jaw having a lug arranged to engage in said recess in the closed position of the movable jaw, a projection projecting radially outward from the radially outward side of said movable jaw and beyond said other end of said movable jaw, a part of said plate remote from said stationary jaw being provided with a notch arranged to conformably receive said projection in the closed position of the movable jaw, and locking means acting between said part of the plate and said projection and engageable with a portion of said projection in the closed position of the movable jaw for releasably retaining the movable jaw in closed position.

4. In a wrench, a pair of complementary semi-circular jaws, one of said jaws being stationary and the other relatively movable, a plate fixed on and extending radially outward from the radially outward side of said stationary jaw at one end of said stationary jaw, said stationary jaw having a free end, said movable jaw having an end pivoted to the free end of the stationary jaw and having another end, said one end of the stationary jaw and said other end of the movable jaw terminating in abutments arranged to engage in the closed position of the movable jaw, one of said abutments being provided with a recess and the abutment of the other jaw having a lug arranged to engage in said recess in the closed position of the movable jaw, a projection projecting radially outward from the radially outward side of said movable jaw and beyond said other end of said movable jaw, a part of said plate remote from said stationary jaw being provided with a notch arranged to conformably receive said projection in the closed position of the removable jaw, said projection and said part of the plate having edges arranged to engage in the closed position of the movable jaw, said edges being provided with slots which register in the closed position of the movable jaw, and

a lock pivotally mounted in one of said slots and swingable from a locking position in which said lock engages in both of said slots so as to positively lock the movable jaw when in closed position to a released position in which said lock is disengaged from the slot in said projection.

5. In a wrench, a pair of complementary semi-circular jaws, one of said jaws being stationary and the other relatively movable, a plate fixed on and extending radially outward from the radially outward side of said stationary jaw at one end of said stationary jaw, said stationary jaw having a free end, said movable jaw having an end pivoted to the free end of the stationary jaw and having another end, said one end of the stationary jaw and said other end of the movable jaw terminating in abutments arranged to engage in the closed position of the movable jaw, one of said abutments being provided with a recess and the abutment of the other jaw having a lug arranged to engage in said recess in the closed position of the movable jaw, a projection projecting radially outward from the radially outward side of said movable jaw and beyond said other end of said movable jaw, a part of said plate remote from said stationary jaw being provided with a notch arranged to conformably receive said projection in the closed position of the removable jaw, said projection and said part of the plate having edges arranged to engage in the
